United States Patent Office

Des. 185,686
Patented July 14, 1959

185,686

KEY SAFE

Theodore A. Tronson, San Jose, Calif.

Application July 21, 1958, Serial No. 51,859

Term of patent 14 years

(Cl. D69—1)

FIG. 1

FIG. 2

FIG. 3

Fig. 1 is a perspective view of a key safe in partially opened condition as seen from the front and one side showing my new design.

Fig. 2 is a perspective view of the key safe of Fig. 1 as seen from the back and left side thereof.

Fig. 3 is a perspective view of the key safe of Fig. 1 in closed condition and as seen from the front and said one side thereof.

I claim:

The ornamental design for a key safe, as shown.
